UNITED STATES PATENT OFFICE

HENRY ALLEN AVERY, OF GROTON, NEW YORK, ASSIGNOR TO L C SMITH & CORONA TYPEWRITERS INC., OF SYRACUSE, NEW YORK, A CORPORATION OF NEW YORK

TYPEWRITING MACHINE

Application filed April 23, 1928. Serial No. 272,121.

This invention relates to improvements in typewriting machines, and has for its object to provide an efficient key-operated mechanism for vibrating the inked ribbon of a visible writing typewriting machine.

One feature of the invention is the provision of a simple and efficient ribbon vibrating mechanism settable to impart two different extents of throw to a bichrome ribbon and to render the mechanism ineffective to vibrate the ribbon.

Another feature of the invention is the provision of effective means for preventing accidental overthrow of the ribbon, when using either zone of the ribbon, in connection with a vibrating mechanism for imparting two different extents of throw to a bichrome ribbon.

Further features of the invention are the provision of a compact and efficient type-bar-actuated mechanism for vibrating a ribbon guide to cover the printing point with either zone of a bichrome ribbon; and the provision of a type-bar-actuated ribbon vibrating mechanism especially adapted for use in a small and flat portable typewriting machine having a case-shifting platen carriage, said mechanism being so constructed and arranged that the vibratory ribbon guide will shift bodily with the platen and have a uniform throw for each color zone of a bichrome ribbon whether the platen be in upper or lower case position. Other features and advantages will appear from the following description.

Parts of the improvements may be used without the others, and variations may be resorted to within the scope of the invention as defined by the claims.

In the accompanying drawings:

Fig. 1 is a longitudinal sectional view of the machine, many of the parts being omitted to show more clearly the case shift mechanism, the bichrome shift and stencil adjustment mechanism for the ribbon vibrating means, and the mountings for certain parts of the ribbon mechanism;

Fig. 2 a detail sectional view showing the mounting of the rotary escapement devices and associated parts of the ribbon mechanism;

Figs. 3, 4, 5 and 6 detail perspective views of various parts of the ribbon mechanism;

Fig. 7 a rear view of the machine cocked up to a position in which the type bar segment is in a vertical plane and the carriage bed in a horizontal plane, the rear part of the main frame being broken away and the vibrator control means being set in "stencil" position;

Fig. 8 a fragmentary bottom view of the machine positioned as in Fig. 7;

Fig. 9 a perspective view showing part of the case shift frame, and also showing those portions of the ribbon vibrating means and its adjusting means which are mounted on the shift frame, together with the elements connected directly therewith;

Figs. 10, 11 and 12 detail side elevations of similar portions of the ribbon vibrating means showing the positions thereof at the end of the impression stroke of a type bar in each of the three adjustments of the bichrome shift and stencil control means;

Fig. 13 a fragmentary view of the machine, on an enlarged scale, looking from the left hand side of the machine, parts of the machine being broken away to show the ribbon vibrating means in side elevation;

Fig. 14 a fragmentary bottom plan view of the machine, on an enlarged scale, showing the ribbon vibrating means in normal position and set for covering the printing point with the upper zone of the ribbon, as in Fig. 13, the view being taken with the machine cocked as in Figs. 7 and 8;

Fig. 15 a front view of the ribbon vibrating means, set for use of the upper zone of the ribbon as in Figs. 13 and 14, the front arcuate portion of the universal bar being broken away, and the view being taken with the machine cocked as in Figs. 7 and 8;

Fig. 16 a section on the line 16—16 of Fig. 15, with parts of the escapement and fixed margin stop bracket broken away;

Fig. 17 a fragmentary view of the machine looking from the right, parts being broken away to show the ribbon vibrating means in side elevation, and the vibrating means being shown in normal position, and

adjusted for vibrating the upper zone of the ribbon to the printing point; and

Fig. 18 a view similar to Fig. 17 showing the positions of the various parts at the end of the printing stroke of a type bar.

The invention has been illustrated as embodied in the "Corona Four" typewriting machine which is constructed, except for the improved key-actuated ribbon-vibrating means and certain modifications of other parts associated therewith and hereinafter pointed out, substantially as shown and described in United States Letters Patent No. 1,700,827, No. 1,700,828, No. 1,700,829 and No. 1,741,689.

The main frame of the machine comprises a front wall 10, a back wall 11, side walls 12, and a transverse partition wall 13 which is located in the rear portion of the main frame with its lower edge above the level of the lower edges of the other frame walls and inclines upward and rearward. A rearwardly inclined type-bar segment 14, having an arcuate recess 15 in its rear face, is held to the front face of wall 13 by suitable screws, with the usual arcuate pivot wire 16 therein lying in a plane parallel with said wall. An arcuate system of type bars 17 are fulcrumed on wire 16 and guided in the segment slots 20 to strike on the upper front quarter of a platen 18. Character key levers 19 are fulcrumed at their rear ends on a pivot wire 20 held to a fulcrum plate 21 secured to the rear face of wall 13 by suitable fastening screws. The key levers extend downward behind wall 13 and then forward under said wall to the keyboard and are guided in a comb member 22 held to the main frame. The connection between each key lever and its associated type bar comprises a bell-crank lever 23 fulcrumed in a sub-lever segment 24 and connected with the type bar heel and key lever by links 25 and 26, respectively. Return spring 167 for the type bar actions 40 connect key levers 19 with a spring anchor bar 166 on the main frame, hereinafter referred to.

The shift frame for the platen carriage 27 comprises a rearwardly and downwardly inclined carriage bed 28 having a pair of rigid downwardly and forwardly extending sheet metal guide members 29 fastened thereto at their upper ends adjacent opposite sides of the machine and connected by a transverse brace rod 30 adjacent their lower ends. The carriage is mounted on the bed in rearwardly tilted position on suitable antifriction bearings, as shown, to travel transversely of the machine, and supports platen 18 above and in rear of the type bar pivots. The carriage and bed overlie the space between frame walls 11 and 13 and the guide members 29 extend down between said walls between cooperating guide members 31 held to the main frame side walls in upwardly and rearward-

ly inclined position, members 29 and 31 being provided with races in which are confined ball bearings, said members and races being so arranged as to guide the carriage and shift frame obliquely in a plane parallel with the plane of the segment, as in said application and machine before referred to.

As in the Corona Four machine, the shift frame is actuated by either of two shift key levers 33 fulcrumed on pivots 38 on brackets 39 held to frame walls 12, said levers having forked rear ends embracing studs 34 on the forward ends of the side arms 35 of a shift torsion and counterbalancing frame which comprises said arms 35 and a rock shaft 36 to which the arms are held. Shaft 36 is journaled on the frame walls 12 between wall 11 and the lower part of the shift frame, and studs 34 are engaged in rearwardly and downwardly extending slots 37 in members 29 of the shift frame. Brackets 39 also support a type bar rest 40.

Downward movement of the shift frame is limited by engagement of stops 41 on members 29 with adjustable stop screws 42 on brackets 43 held to frame walls 12. Upward movement of the shift frame is limited by the engagement of adjustable stop screws 44 on members 29 with stops 45 on brackets 43. The frame 35-36 is arranged to counterbalance the shift frame by connecting lugs 46 on arms 35 with the lower ends of counterbalancing springs 47 which are secured at their upper ends to arms 48 of brackets 43.

An arcuate sheet metal universal bar 49, adapted to be engaged and moved rearwardly by lugs 17* on the type bars during the latter part of the printing strokes of the type bars, is located between segment 14 and wall 13 and is supported in a plane parallel with the planes of said wall and segment to vibrate in the segment recess 15 in a path substantially perpendicular to said planes and the rearwardly inclined plane in which the type bar pivot wire 16 in the segment lies. Universal bar 49 is carried at the forward ends of a pair of rearwardly and downwardly extending two-part sheet metal side arms comprising front sections 50 and 51 and rear sections 50* and 51*. Sections 50 and 51 are formed integrally with the universal bar, as shown, and extend through apertures 52 affording clearance openings through wall 13 and fulcrum plate 21. The front portions of sections 50* and 51* are rigidly but detachably clamped to the rear portions of sections 50 and 51 by pairs of screws 54.

Sections 50* and 51* of the side arms are offset laterally inward at the rear ends of sections 50 and 51, and are provided with longitudinal guiding and supporting slots 53 in their offset rear portions extending perpendicular to the plane of the segment. These slots are open at their rear ends and

correspond in width with the diameter of rock shaft 36 which extends therethrough and upon which the side arms are thus slidably supported and guided at their rear ends 5 to reciprocate fore-and-aft of the machine. A transverse spacer bar 55 formed integrally with section 50^a forward of shaft 36 abuts the inner face of section 51^a.

The side arms extend from universal bar 49 through the shift frame and the shift torsion frame to points adjacent the lower edge of wall 11, and are supported and guided intermediate the universal bar and shaft 36 on fore-and-aft rocking arms 56 and 57, fixed 10 at their lower ends on a short transverse rock shaft 58. Shaft 58 has trunnions 58^a journalled on the inner ends of bearing screws 59 threaded inward through the rear ends of a pair of arms 21^a which are formed integrally 15 with fulcrum member 21 and extend rearward and downward to a point forward of shift frame rod 30 and close to the base line of the main frame. Arms 56 and 57 extend upward and rearwardly forward of shift frame rod 30 at a slightly less angle from the vertical than the wall 13 and shift frame and have pivot holes in their ends in which are engaged reduced pivot portions of pivot and spacing studs 61 and 64, the reduced outer 20 supporting ends of the studs being swaged tightly in apertures in the arm sections 50 and 51, respectively, forward of arm sections 50^a and 51^a. Stud 64 has a reduced and headed extension 64^a extending inward from its 25 pivot portions for supporting and guiding a part of the ribbon vibrating mechanism.

The universal bar is normally held at the forward limit of its movement against the front wall of recess 15 in the type bar segment 40 14 by a return spring, hereinafter described, and its extent of throw by universal bar contacting lugs 17^a on the type bars 17 is such that the pivot studs 61 and 64 and upper ends 45 of rock arms 56 and 57 swing between points substantially equal distances at opposite sides of a plane through the axis of rock shaft 58 perpendicular to the plane of the carriage bed and parallel with wall 13. The arrangement and movement of rock arms 56 and 57, 50 together with the arrangement of slots 53 longitudinally of the side arms and perpendicular to the plane of wall 13, provides for supporting and guiding the universal bar 49 55 to vibrate obliquely to the horizontal plane of the machine in a path substantially perpendicular to the plane of the segment and its type bar pivot wire.

The escapement and line-locking mechanism are constructed as in the Corona Four machine, with the exceptions hereinafter pointed out, and need only be so far described as to permit a full understanding of the present invention. A sheet metal bracket 65 has 60 its flat body part held by screws 66 against

the bottom face of carriage bed 28 and extending across an opening 85 in said bed. A steel bushing 67 extends through, and is tightly swaged in, an opening in said body part of the bracket and is formed with a narrow cylindrical hub portion 67^a abutting the said bracket at its upper end, said hub portion being of less diameter than the lower end of the bushing to provide an annular seat 67^b parallel with said body part of the bracket for a line-lock member, hereinafter described, pivoted on said hub.

Bracket 65 is formed with rearwardly and downwardly extending side arms 68 and 69 carrying at their rear ends horizontal pivot screws 70 having reduced pivot ends engaged in bearing apertures in pendent pivot ears 72 and 73 formed at the ends of the flat body part of a sheet metal dog rocker 74. A rigid holding dog 75, formed on the forward edge of rocker 74, and a feeding dog 76 (pivoted on the rocker at 77 and controlled by a suitable spring and stop device), cooperate with a toothed escapement wheel 78 to control the feed of the carriage. Wheel 78 in the present construction is formed with a pendent hub 78^a and is fixed on the lower end of a shaft 79 journalled in bushing 67 and carrying a feed pinion 80 at its upper end meshing with a rack 81. Rack 81 lies between the carriage base plate and carriage bed and is formed integrally with a portion of the carriage base plate as in the Corona machine. The carriage 27 is normally urged toward the left by the usual spring drum 82 which is held to the carriage bed at 83 and is connected in the usual way by a suitable cable with the carriage. Pinion 80 is adapted to pass through opening 85 in the bed 28, so that bracket 65 together with the parts mounted thereon is removable from and attachable to the bed as a unitary assemblage.

In the present construction the escapement shaft is prolonged downward to a point above the level of the universal bar side arms and is formed with a circumferential groove 86 closely adjacent its lower end in which is engaged a bendable horseshoe shaped key 87 between which and the lower end of the escapement wheel hub is confined the main body part of a lever forming part of the ribbon vibrating means, which lever as herein-after described is pivotally supported on the shaft 79 and the hub 78^a of the escapement wheel 78.

In the present construction also the prolonged portion of the shaft below the bushing is formed with longitudinal grooves 88 into which are firmly screwed the inner end of set screws 89, threaded through the hub of the escapement wheel, for holding the wheel to the shaft. The outer ends of screws 89 are countersunk within the periphery of the hub 78^a which is free from other projections and is cylindrical.

Dog rocker pivot ear 73 is formed with a forwardly extending stop arm 90 formed with an upstanding rearwardly facing hook lug 90^a the upper end of which normally abuts the bottom face of bracket 65 adjacent the inner side of bracket arm 69 to arrest return movement of dog rocker 74 under the pull of the rocker return spring 91. Spring 91 is connected at its rear end with a lug 92 projecting laterally outward from the lower end of rocker pivot ear 72 and is connected at its forward end with a pendent lug 93 on bracket arm 68. The feeding dog 76 normally engages a tooth of the escapement wheel 78 with holding dog 75 above the plane of the wheel. The rocker is provided with an arm 94 depending from its pivot ear 73 and formed with an outwardly extending contact lug 95 at its lower end lying flatwise in a plane perpendicular to wall 13 and the path of movement of the shift frame. The rocker is adapted to be rocked through the medium of said arm 94 and lug 95, to disengage dog 76 and engage dog 75 with escapement wheel 78, by tappets 96 and 97 movable, respectively, with the type-bar-actuated universal bar 49, and a space bar (not shown), said tappets being located forward of lug 95 with their rear lug-contacting edges parallel with the path of shift of the shift frame.

Tappet 96 is rigid with and formed on the rear end of side arm 50 of the universal bar and, in the machine shown, is normally spaced slightly forward of lug 75. Tappet 97 is formed on the rear end of a bar 98, and is normally substantially engaged by lug 95, as shown. The bar 98 is guided to move rearward and downward upon depressions of the space bar, being provided with a downwardly inclined guide slot 99 in which engages a stud 100 projecting outward from rock arm 56, as in the machine hereinbefore referred to.

A plate 101 formed of sheet metal is held to the carriage bed 28 by screws 102 and 103 passing through a forwardly extending base flange formed on said plate and underlying the bed. Plate 101 extends up behind the rear raceway of the carriage where it is formed with a carriage stop lug 113^a.

50 A right hand margin stop 104 is mounted on the margin stop bar 105 carried by the platen carriage and is adjustable along said bar as in the Corona machines. Stop 104 is formed with a pendent stop lug 104^a at its lower end adapted to engage and operate a line-locking member. The line-locking member comprises a sheet metal latch lever or pivoted plate 112 having its flat body part underlying bracket 65 and held flat against the bottom face of said bracket by the annular upwardly facing seat or shoulder 67^b on bushing 67, said plate having a slot 106 therein extending rearward from the forward edge of said plate and rounded at its rear end so that the rear end and rear portions

of the side walls of the slot hug the periphery of the hub section 67^a of the bushing. Slot 106 thus forms a pivotal bearing aperture in the plate adapted to receive hub 67^a and open at one side so that the plate may be slipped edgewise on and off its pivot.

70 Plate 112 is formed with a rearwardly facing notch 107 in its rear end, downwardly into which projects the thickened head of the right hand fastening screw 103 for plate 101, said screw head being of less diameter than the width of the notch 107 at the point where said screw head extends into the notch. The left hand wall of notch 107 forms a stop face normally held engaged with the head of screw 103 by coil spring 108, with the stop face formed by the opposite wall of said notch spaced from said screw head. Spring 108 in the present construction is connected at its rear with the outer end of an integral arm 109 extending toward the right from the rear end of the plate 112 to a point adjacent bracket arm 68, while the forward end of the spring is connected to an arm of the ribbon guide vibrating bell crank, herein-after described, to yieldably hold both of the members in normal position. Spring 108 not only normally holds plate 112 rocked toward the right, but also exerts a constant forward pull on said plate to prevent accidental detachment of the plate from its pivot hub.

75 Arm 109 is offset upward intermediate its ends in rear of plate 101 and formed with a stop lug 110 projecting rearward therefrom and having a straight rearwardly extending right hand edge normally in the path of travel of stop lug 104^a of margin stop 104. Plate 112 is formed with a latch arm 111 offset downward therefrom and normally extending rearward and to the left from the left hand edge of plate 112 and clearing the relatively thin head of fastening screw 102 of plate 101.

80 Arm 111 is normally located in rear of the recess or throat of the rearwardly facing hook lug 90^a on dog rocker arm 90 and is adapted to swing into said recess when plate 112 is rocked toward the left against the pull of spring 108 (until arrested by engagement of the right hand edge of notch 107 with the head of screw 103) through the engagement with lug 110 on member 112 of lug 104^a of margin stop 104 as the carriage is fed toward the left. When this occurs, the dog rocker is positively locked in normal position so that the carriage cannot be fed farther toward the left. Since the dog rocker cannot tilt, if a character key is depressed, its connected type bar 17 will simply swing up to the position where the universal bar had moved slightly rearward and been arrested by tappet 96 striking lug 95 on the locked dog rocker. As the universal bar is thus arrested forward of its normal rearward limit of travel, it blocks the completion of the printing stroke of the 85 90 95 100 105 110 115 120 125 130

type bar and thereby prevents making of superimposed impressions upon the work sheet. The line may be unlocked as in the Corona machine, by means not herein shown, and 5 advance of the carriage continued until stop 104 strikes the fixed stop or lug 113 on plate 101.

The ribbon vibrator, or reciprocatory ribbon guide, 113 is slidably guided on the type 10 guide 114 to vibrate up and down in a plane parallel with the plane of the segment and the plane of case-shift movement of the platen. Type guide 114 is constructed and attached to wall 13 by screws as in the machine 15 and applications before referred to, having a flat main body portion lying parallel with the plane of the segment and provided with a type bar guiding throat 115 at its upper end and a longitudinal slot 116 extending up 20 ward from its lower edge. Ribbon guide 113 lies behind the type guide and consists of a flat sheet metal plate provided at its upper end with ribbon guiding slots and intermediate its ends with angular guide lugs 117 25 embracing the sides of the type guide, all as in the machine referred to.

In the present construction, ribbon guide 113 is formed at its lower end with a central pendent tongue bent rearwardly at 118, and 30 then bent successively forwardly, downwardly, and rearwardly to form a rearwardly and downwardly facing U-shaped socket 119. The front wall of socket 119 lies immediately forward of the plane of the front face of the 35 type guide and in the same inclined plane as the inwardly bent forward ends of lugs 117 and is formed with lateral guide lugs 120 lying in the plane of said front wall and overlapping the front face of the type guide at 40 opposite sides of slot 116.

Socket portion 119 of the ribbon guide slidably works in slot 116 to assist lugs 117 to hold the ribbon guide against lateral tilting, while lugs 117 and 120 on the one hand, 45 and the flat main body of the ribbon guide on the other hand, work against opposite faces of the inclined flat body part of the type guide to maintain the ribbon guide in the plane of the segment during vibratory 50 movement thereof.

A bichrome inked ribbon 121 is reeled on the ribbon spools 122 and threaded through 55 guide slots in vibrator 113. The spools and their pawl and ratchet rotating devices are mounted on brackets 123 held to carriage bed 28 at opposite sides of the machine as in the Corona Four machine.

Ribbon vibrator 113 is reciprocated, and is 60 also supported to shift bodily in unison with the platen during case shifting, by a vibrator actuating bellcrank 124 pivotally mounted in a bracket 126 detachably held to the bottom face of the carriage bed 28 by screws 127. Bracket 126 takes the place of a similarly located bracket in the Corona machine and

is formed at its front edge with a pair of upwardly and rearwardly inclined lugs 128 for supporting the line gauge and printing point indicator of the machine, but in the present construction the flat body part of the 70 bracket is formed with a pair of integral pendent pivot lugs 125 for bellcrank 124 lying flatwise in fore-and-aft extending and transversely spaced planes and provided with bearing apertures for the shouldered pivot 75 portion of pivot screws 129, the reduced threaded ends of which are screwed into threaded holes in the upper parts of pendent arms 130 and 131 of bellcrank 124.

The bellcrank 124 is formed of sheet metal 80 and consists of a transverse bar-like body part which is formed at its ends with the integral pendent arms 130 and 131, and is formed intermediate its ends with a forwardly extending integral arm 132 extending toward the type guide. Arm 132 has its front end bent to lie edgewise in a vertical plane and terminates in an enlarged bearing head 133 the top and bottom edges of which are rounded. Head 133 is engaged in socket portion 134 of the ribbon guide, thereby affording a separable rocking connection between the bellcrank and the guide. Bellcrank arm 131 is bent horizontally outward below its pivot ear, and this outwardly bent arm portion 90 is formed at its rear edge at its outer end with an integral pendent stop lug 134 lying flatwise in a transverse plane and normally held back against a fixed abutment on the shift frame, namely the front edge of the 95 lug 93 on escapement bracket arm 68 to which the front end of dog rocker return spring 91 is anchored. The bellcrank is yieldably held in this normal position, with the ribbon guide lowered to retract the ribbon from in front of the impact point on the platen, by the spring 100 105 108 hereinbefore referred to, the front end of this spring being anchored to the horizontal portion of bellcrank arm 131 and its rear end to the arm 109 of the pivoted line-locking 110 member 112 before described. Stop lug 134 is bendable fore-and-aft of the machine to adjust the normal fore-and-aft position of the pendent arm 130 of the bellcrank 124.

Bellcrank 124 is rocked in opposition to 115 spring 108 by an actuating lever 135 to cause the ribbon to cover the printing point. This lever is an upstanding and fore-and-aft rockable lever having a single arm, is axially shiftable to either of three different positions relatively to the pendent arm of the bellcrank, and has a rocking movement of the same amplitude about its axis in each of said positions. The axial setting of lever 135 determines the amplitude of throw of the bellcrank, which is nil in one setting for writing stencils, short in another setting for causing the upper (usually black) zone of the ribbon to cover the printing point, and longer in the third setting for causing the lower (usually 120 125 130

red) zone of the ribbon to cover the printing point.

Lever 135 is stamped from sheet metal and has a yoke-like main body portion of U-shape in plan view, affording a broad flat contact wall 138 for an actuating tappet extending transversely of the machine and a pair of forwardly extending side walls 139 and 140. Wall 138 is formed at its lower end with a pendent tail-piece 137 terminating in rear of brace rod 30 of the shift frame. Connected with the forward edges of walls 139 and 140 by integral bendable tongues of metal are a pair of fore-and-aft bendable upstanding tappet or contact fingers 141 and 142 lying flatwise in the planes of the walls 139 and 140, respectively.

The main body portion of the lever 135 is formed with a pair of pendent transversely spaced guiding and pivot ears 143 and 144 below walls 139 and 140, respectively, lying in fore-and-aft planes and provided with circular bearing holes 145 through which brace rod 30 passes loosely, affording a sliding and pivotal mounting for lever 135 at its lower end on the shift frame. Lever 135 is normally spring retracted and supported in upstanding position, as hereinafter described, and is rocked forwardly by a two-armed tappet lever 146. Lever 146 is formed of sheet metal and has its flat body portion 146 fitted between the flat lower end of escapement wheel hub 78^a and the escapement shaft key 87 and provided with a bearing aperture 147 through which 35 the escapement shaft 79 extends and also with an integral upwardly offset bearing ring 148 encircling the upper end of hub 78^a and connected by a web 149 with the main body part of the levers, thus affording a steady bearing 40 for the lever for rocking about said shaft and hub in a plane perpendicular to the plane of movement of the case-shift frame.

An integral arm 136 extends forward from pivot ear 144 of lever 135 between the lower pivoted end of said ear and finger 142 and has its forward end bent toward the left hand side of the machine to form a short transversely extending bell-crank-arm blocking portion 136^a spaced forward of the lower end 50 portion 130^a of the pendent bellcrank arm 130 when the lever 135 and bellcrank 124 are held retracted by their return springs. Portion 136^a is of such short length that it does not extend into the path of the abutment portion 130^a of bell-crank arm 130 except when the lever 135 is at that one of its three axially adjusted positions nearest the left hand side of the machine.

Abutment portion 136^a is so located that the 60 rear side thereof is engaged by the forward edge of the lower abutment portion 130^a of bellcrank arm 130 located below the lower-most pin at the instant the ribbon guide reaches its position for covering the printing point on the platen with the upper zone of

the ribbon when lever 135 is in its short throw imparting position. Arm 130 and lever 135 swing in opposite directions about parallel axes on the printing strokes of the type bars and abutments 130^a and 136^a are so located relatively to the axes of the levers carrying the same that abutment 130^a will overtake and will be thrust against abutment 136^a through the thrust of finger 142 on pin 176, as hereinafter described.

The body part of lever 146 is formed with a tappet-carrying arm 150 extending toward the left hand side of the machine and formed with an integral pendent tappet 151 disposed edgewise in a fore-and-aft plane behind contact wall 138 of lever 135, said tappet preferably having a forwardly projecting rounded nose portion contacting said wall, as shown. The body part of lever 146 is also formed with an arm 152 extending toward the right hand side of the machine through a slot 153 in a fore-and-aft reciprocable ribbon actuator 154 which is so mounted in the main frame as not to partake of the case-shift movement of the shift frame.

Ribbon actuator 154 consists of a sheet metal bar disposed edgewise in a vertical plane and having the transverse slot 153 intermediate its ends, open at the top and extending parallel with the plane of shift of the shift frame, and also having the longitudinal open-ended slots 155 and 156 at its front and rear ends, respectively, extending parallel with the path of movement of the universal bar and perpendicular to the path of shift of the shift frame. Actuator bar 154 is also formed with an integral pendent arm 157 adjacent its front end extending down between rod 30 and shaft 58. The slotted forward end 155 of ribbon actuator 154 is guided and supported in and by the circumferentially grooved inner end 64^a of pivot stud 64 carried by universal bar side arm section 51, and the slotted rear end of the rearwardly and downwardly extending actuator is guided and supported in a circumferential groove 158 in the rock shaft 36 forming part of the shift torsion frame.

The slots and supports are so arranged that actuator bar 154 is movable endwise rearwardly and downwardly by the universal bar through the medium of stud 64 in a path perpendicular to the path of shift of the shift frame. The described method of mounting and actuating bar 154 permits rearward movement of the bar either by, or independently of, the universal bar, and also affords a simple mounting and operating means for the actuating bar.

In the machine shown, the ribbon feeding and reversing devices are also actuated from bar 154, and the capacity for independent movement of bar 154 is utilized in connection with the typing of accent characters, by means not shown herein. The ribbon actu-

ator 154 and universal bar 49 are returned to normal position by a return spring 159 connected with the actuator shaft 164 for the ribbon spool driving and ribbon feed reversing devices of the machine, said return being assisted, except during stencil writing, by the common return spring 108 for the vibrator actuating bellcrank 124 and line-locking lever 112. The ribbon feeding and reversing devices and actuating shaft 164 therefor are constructed as in the machine and applications referred to and need only be briefly described.

The ribbon spools 122 rotate with ratchets 160 on the brackets 123 held to the carriage bed 28, said ratchets being driven by pawls 161 pivoted on brackets 123 and connected by links 162 with upstanding rock arms 163 fixed on the actuating rock shaft 164. Shaft 164 is journaled on the main frame and lies under wall 13, and the left hand rock arm 163 is extended downward below the shaft to provide a pendent rock arm 165 connected by the return spring 159 (above referred to) with a spring anchor bar 166 mounted in the main frame of the machine to which the type bar action return springs 167 are also connected. Arms 163 carry tappet hooks 168 at their upper ends for actuating the ribbon-abutment settable trip devices 169 to throw one pawl 161 out of action and the other pawl into action by the pawl-controlling means of the Corona machine not herein shown. About midway its ends rock shaft 164 is provided with a pendent rock arm 170 for oscillating the shaft at the type strokes.

All the foregoing parts of the ribbon feeding and reversing means are constructed as in the Corona Four machine and the applications referred to above. In the present construction, pendent rock arm 170 is positively connected by a rigid fore-and-aft extending wire link 171 with the outwardly bent lower end of pendent arm 157 of the reciprocable ribbon actuator 154, said link 171 extending under one of the reduced trunnion portions 58^a of rock shaft 58 and lying substantially at the level of the base line of the main frame.

Spring 159 normally rocks shaft 164 in a direction to cause link 171 to draw actuator bar 154 forward, and said bar, through engagement of the rear end of slot 155 with part 64^a of stud 64, normally pushes the universal bar 49 forward until return movement of these parts is arrested by the abutment of the front edge of the arcuate universal bar 49 with the front wall of recess 15 in type bar segment 14. Since tappet lever 146 is interlocked with actuator 154 its normal position is also fixed by this arrest of the universal bar. The normal return position of bell crank actuating lever 135 is also determined by this arrest of the universal bar through abutment of wall 138 of the lever 65 with tappet 151 on tappet lever 146. The

segment 14 thus serves as a stop to determine the normal position of the bell-crank-actuating parts of the ribbon mechanism. The normal position of bell-crank 124 is determined by stops 134 and 93.

Lever 135 is axially slideable on rod 30 to disconnect it from the bellcrank 124 at one point, and either leave it disconnected for stencilling, or to reconnect it with the bellcrank at another point. The lever is guided by rod 30 and tappet 151 during axial sliding adjustment thereof, and in order to hold the lever back against the tappet a light spring 172 is provided. In the construction shown, spring 172 is connected at one end with an eye 173 punched rearward from tail piece 137 of lever 135 and extends upward and rearward therefrom to the transverse body part of dog rocker 74 to which its upper end is attached by passing its upper hooked end about the web of metal between the rear edge of the rocker and one of the stop eyes 174 punched down from the rocker with which the pair of pivoted spring-connected feed-dog controllers of the Corona machine 90 cooperate.

Spring 172 is preferably of light tension, only strong enough to hold up the lever 135 against the tappet and to return this lever, alone, when the keys are actuated. Spring 172 is only very slightly stretched on the down strokes of the keys until tappet 96 picks up the dog rocker, after which the lever 135 and dog rocker 74 swing together in the same direction without appreciable tensioning of the spring during the remaining part of the down strokes of the keys. This arrangement, together with the light normal tension of the spring, provides in a simple way for the before described sustaining of lever 135 and return thereof without adding an appreciable load to the ribbon vibrating means during operation of the machine.

The pendent arm 130 of vibrator actuating bellcrank 124 has rigidly attached thereto, above abutment portion 130^a two laterally projecting short pins or studs 175 and 176 located different distances from the pivotal axis of the bell crank and at different sides of arm 130, said pins having reduced portions passed through holes in arm 130 and headed over against the arm. The U-shaped or yoke-like body part of lever 135 embraces the lower end of arm 130 of the bellcrank, and wall portions 139 and 140 of this part of lever 135, with their attached fingers 141 and 142, are spaced apart sufficiently to clear the outer ends of both of the pins 175 and 176 when lever 135 is in its intermediate axially adjusted position. This yoke portion is of such depth fore-and-aft that wall 138 will not engage arm 130 of the bellcrank during stencil operations.

Finger 141 is moved directly in rear of pin 12^a

- 175 when lever 135 is shifted toward the right from its neutral or stenciling adjustment position, and finger 142 is moved directly in rear of pin 176 when lever 135 is shifted toward the left from neutral position. Fingers 141 and 142 preferably have straight pin-pushing front edge portions 177 and 178 and extending upwardly in the same direction, and said fingers and their coercive pins 175 and 176 are preferably located different distances from the axis of lever 135 and the axis of bellcrank 124, as shown, so that when pin 175 is engaged with finger 141 the effective length of lever 135 is increased and the effective length of bellcrank arm 130 is decreased, whereas, when finger 142 is engaged with pin 176, the effective length of lever 135 is decreased and the effective length of arm 130 is increased, thus affording a compact arrangement for imparting the long and short throws of necessary extent to the vibrator bellcrank from an actuating lever having a short throw of constant amplitude imparted by a type-bar-actuated universal bar which, in the machine shown, as is usual, is only moved by the type bars during the latter portion of the printing strokes of the type bars.
- The edge portions 177 and 178 of fingers 141 and 142 are made sufficiently long to maintain contact between each of said edge portions and its cooperating pin during the full rearward stroke of the universal bar and to permit such adjustment of the fingers 141 and 142 and bendable obstructing portion 136^a of arm 136 as may be necessary to give proper amplitudes of movement to the vibrator for using the two zones of the ribbon. Portion 136^a of arm 136 is bendable fore-and-aft of the machine to vary its normal distance forward of the lower end of the pendent arm of bellcrank 124.
- When the lever 135 is adjusted for the short throw of the vibrator the lower end portion 130^a of bellcrank arm 130 engages behind portion 136^a of arm 136 on lever 135 at a point below pin 176 and its actuating tappet or push finger 142 as the type reaches the platen, thus affording a cramping interlock between the bellcrank and its actuating lever which will prevent overthrow of the ribbon guide which might otherwise result from acquired momentum of any or all of the parts of the ribbon vibrating train.
- The adjustment of lever 135 to its position for effecting the long throw of the ribbon guide withdraws blocking portion 136^a laterally from the path of movement of abutment portion 130^a of pendent arm 130 of bellcrank 124. In order to prevent overthrow of the ribbon guide while lever 135 is set for the long throw, an overthrow preventing stop device is provided which is effective only during such adjustment of the lever. This latter overthrow preventing

means comprises a movable stop 179, consisting of an integral lug extending forward and upward from the front edge of the transverse body part of bellcrank 124 and bendable up and down for purposes of adjustment, and a fixed stop consisting of the bottom face of the main body part of bracket 126. On the short throw of the vibrator, lug 179 (as shown in Figs. 10 and 18) does not move far enough to strike bracket 126, but said lug is adjusted so as to strike the bottom face of the bracket adjacent the forward edge of the bracket (as shown in Fig. 11) on the long throw of the vibrator as the type reaches the platen.

The color shift and stencil control means for axially adjusting lever 135 to vary the amplitude of throw of the vibrator 113 for using different zones of the ribbon, and to render the vibrator inactive for writing stencils, extends to the left hand side of the keyboard of the machine for convenient operation. The key lever guide comb 22 is formed at its ends with attachment lugs 180 abutting the inner faces of side walls 12 of the main frame and held thereto by pairs of screws 181 passed inward through the walls and threaded through the lugs. The inner ends of fastening screws 181 for lug 180 at the left hand end of the comb are also threaded through the rearward extending arm 182^a of an upright sheet metal bracket 182 to detachably hold said bracket to the left hand frame wall 12. Arm 182^a extends through a notch or slot 22^a in comb 22, and the main body of bracket 182 extends upward flatwise alongside wall 12 forward of the comb and is formed at its upper end with an inwardly bent flange 183 disposed substantially horizontally.

Flange 183 is formed with a fore-and-aft extending slot 183^a having its inner edge provided with a central locking notch 184 and two end locking notches 185 and 186 which notches are adapted to receive the handle arm 187 of a sheet metal bell-crank hand lever. Lever arm 187 is spring tempered and normally bowed toward the right, to automatically spring into the locking notches, and extends up through slot 183^a, being provided at its upper end with a finger piece 188 for rocking the lever and for flexing it toward the left out of the locking notches.

This hand lever is pivotally held to the lower end of bracket 182 at a point forward of the comb 22 by a transverse pivot screw 189, and has an arm 190 extending rearward through comb notch 22^a and then upward a short distance behind the comb. A sheet metal bar 191 is pivotally connected at its front end by a transverse pivot screw 192 with the free end of hand lever arm 190, and extends rearwardly under sub-lever segment 24 and over spring anchor bar 166 to a point under partition wall 13. Anchor bar 166 is

held in slots in the forward ends of a pair of fore-and-aft adjustable sheet metal bars 193 clamped to arms 43^a, extending forward under wall 13 from brackets 43, by pairs of clamping screws 194 which pass through 5 longitudinal slots in bars 193 and are threaded into the bracket arms 43^a, for adjusting the tension of the type bar action return springs 167.

10 In the present construction, the rearmost one of the pair of screws 194 at the left hand side of the machine is shouldered between its head and the inner face of the adjacent bar 193 (see Fig. 8), and bar 191 is provided with 15 an open ended longitudinal slot 195 in its rear end through which said shouldered portion of the screw extends to slidably support and guide the rear end of the bar 191 which is confined between the screw head and inner 20 face of bar 193, said slot 195 extending rearward and downward so that bar 191 (guided by said slot and the upward and rearward extending arm 190 of the hand lever 187) will move obliquely substantially perpendicular to the plane of the shift frame when 25 the hand lever is rocked.

In rear of sub-lever segment 24, arm 191 is formed with an integral upstanding finger 196, bendable fore-and-aft for adjustment 30 purposes, to which is pivotally connected the forward end of a rigid wire link 197 which extends rearward and downward under wall 13 to a point adjacent the lower end of the left hand shift frame member 29 where it is 35 pivotally connected with the outwardly extending arm 198 of a sheet metal bellcrank lever 199 pivoted on said shift frame member. As shown in Fig. 1 the link 197 is so arranged that its rear end will move, when 40 the shift frame is shifted from one case position to the other, between points located equal distances below and above an oblique plane perpendicular to the plane of shift of the shift frame and passing through the point of connection of the forward end of the link 45 with finger 196, so that the action of the hand lever on the bell crank 199 will be the same in either case position of the shift frame and the adjustment of lever 135 will not be disturbed by case shift movements of the shift frame.

In the Corona machine previously referred to, the upper case stop screws 44 are carried by the outer ends of a pair of sheet metal bars 200 each fastened by two screws 201 to the under faces of lugs 202 stamped forward out of the main transverse body portions of the shift frame members 29, said lugs lying flatwise in a plane perpendicular 55 to the plane of movement of the shift frame. In the present construction, a simple and efficient mounting for bellcrank 199 on the shift frame is afforded by substituting a long shouldered pivot screw (indicated at 201^a) 60 for the outermost one of the pair of fasten-

ing screws for the left hand stop carrying bar 200, the long bearing or shoulder portion of the screw 201^a depending below bar 200 and lug 202 parallel with the path of shift of the shift frame, and by forming the 70 middle portion of bellcrank 199 with two superposed pivot ears 203 through which said bearing portion of screw 201^a extends, the lower ear resting on the head of the screw and the upper ear engaging under 75 bar 200.

To the right of pivot ears 203, bellcrank 199 is provided with an arm 204 extending rearward through the aperture 205 in shift frame member 29, afforded by the stamping out of lug 202, and connected in rear of member 29 with lug 46 on the adjacent rock arm 35 of the shift torsion frame by a coil spring 206 which normally draws said arm toward the left until arrested by engagement of a stop lug 207 on said arm with the front face of member 29. A rigid wire link 208 connects the rear end of arm 204 of bellcrank 199 with the tail piece 137 of the axially adjustable 80 actuating lever 135 for the ribbon vibrator 85 operating bellcrank 124.

Link 208 is permanently bendable to vary its length for proper axial positioning of lever 135. Stop lug 207 is bendable fore-and-aft for purposes of adjustment and engages member 29 to prevent spring 206 from rocking bellcrank 199 far enough to cause the left hand side of lever 135 to bind or rub on the adjacent sectional side arm of the universal bar when the vibrating mechanism 90 is set for the short throw of the ribbon vibrator. Spring 206 constantly tends to take up any slack in the operating train for adjusting lever 135, so that the lever will be yieldably maintained in the desired one of 95 its axially adjusted positions, when the link 208 is once adjusted to proper length, notwithstanding the fact that there is or may be a certain amount of lost motion in the 100 lever adjusting train.

110 The operation of the ribbon mechanism is as follows:

When the handle arm of the adjusting lever 187 is pulled forward and engaged in notch 185 of bracket 182, bellcrank 199 is 115 rocked to the position shown in Figs. 1 and 9 with stop 207 engaging bracket 29, and lever 135 is drawn toward the left and held at the limit of its axial movement in that direction by link 208. In this position of lever 135, pin 176 projects across the front edge 178 of finger 142 immediately in front of said finger while pin 175 is withdrawn laterally from in front of forward edge 177 of finger 141 of the lever. On the down stroke of the character key on any one of the character key levers 19, the lug 17^a on the type bar 17 actuated by said key lever engages with the forward edge of universal bar 49 during the last part of the printing 120 125 130

stroke of the type bar and pushes the universal bar rearwardly, the parts moving from the position thereof shown in Figs. 9, 13, 14, 15, 16 and 17 to that shown in Figs. 10 and 18 with the upper (usually black) zone of the ribbon interposed between the printing point on the platen and the type at the moment of the type impact.

- The parts are moved to and positively arrested in this last position as follows: Extension 64^a of the pivot stud which connects the right hand side arm 51 of the universal bar with rock arms 57 pushes rearwardly the reciprocable actuator 154 through engagement of the stud with the rear end of slot 155 in the actuator. Actuator 154 rocks tappet lever 146 to swing tappet 151 forward through the engagement of arm 153 of the lever in slot 153 of the actuator; tappet 151 rocks lever 135 forward; finger 142 pushes forward on pin 176 to rock bellcrank arm 130 forward; and bellcrank arm 132 moves ribbon guide 113 upward until all parts of this type-bar actuated train are arrested at the end of the type bar stroke by the lower end portion 130^a of bellcrank arm 130 being thrust forward against abutment portion 136^a of arm 136 of lever 135.

Abutment portions 130^a and 136^a of the bellcrank and its actuating lever come into engagement only at the end of the type bar stroke at which time the upper zone of the ribbon is interposed between the type and platen and such engagement together with the bellcrank swinging engagement of finger 142 and pin 176 causes arm 130 and lever 135, which are moving in opposite directions about two parallel axes to become interlocked in such a way that continued movement of either is impossible, each lever taking a cramping grip on the other which prevents overthrow of the ribbon guide which is positively connected with the bellcrank arm 132. It will be seen from Figs. 10 and 18 that stop 179 on the bellcrank 124 does not move far enough to engage bracket 126 on the short throw of the ribbon guide.

On the rearward stroke of the universal bar the escapement dog rocker is actuated as hereinbefore described to the position shown in Fig. 18 by tappet 96. The rearward movement of ribbon actuator 154 rocks shaft 164 through arms 154 and 170 and connecting link 171 to throw arms 163 forward and rock the ribbon spool rotating pawls 161 through links 162 connecting said pawls with arms 163 to turn the spool on which the ribbon is being reeled. This rocking of shaft 164 swings arm 165 rearward and stretches return spring 159.

On the up stroke of the actuated character key, the several type bar actuated parts of the ribbon mechanism are returned to normal position by the action of springs 159 and 108, assisted somewhat by spring 172 and dog

rocker return spring 91, the normal position of the bell crank actuating parts of the ribbon vibrating mechanism and of the ribbon spool ratchet rotating parts of the ribbon feed mechanism being determined by the abutment of universal bar 49 against the front wall of recess 15 in segment 14. The bellcrank and ribbon guide are returned by spring 108 to a normal position determined by the engagement of stops 134 and 93, said spring normally yieldably holding the bellcrank and its pins in a predetermined position relatively to lever 135 so that fingers 141 and 142 on lever 135 may be alternately shifted into operative position behind their co-acting pins, or both positioned out of line with their coacting pins, by axial shifting of the lever 135 which is guided to slide in a predetermined normal plane by rod 30 and the sliding engagement between flat transverse wall 136 of the lever 135 and the nose of tappet 151 on lever 146.

To set the vibrating mechanism for the long throw of the guide to use the lower (usually red) zone of the ribbon, hand lever 187 is rocked to the opposite limit of its throw and engaged in locking notch 186 in bracket 182, thereby sliding lever 135 axially toward the right to a position in which pin 175 is positioned across the forward pin-pushing edge 177 of finger 141 on lever 135 and pin 176 is entirely withdrawn from in front of finger 142, this position of the lever 135 being slightly to the right of that shown in Fig. 7 wherein both pins are shown out of the path of their actuating fingers with lever 187 set as in Fig. 8.

It will be observed that this new connected relation of lever 135 and arm 130 of bellcrank 124 withdraws abutment 136^a on lever 135 from the path of part 130^a of the bellcrank 124 and also changes the leverage by establishing a motion-transmitting connection between said lever and bellcrank and farther from the axis 30 of the lever than that established by the previously described setting for the short throw. The increase in effective length of actuator lever 135 and decrease in effective length of the actuated bellcrank arm 130 is such that the guide is given a substantially greater throw from lever 135 in the new setting although lever 135 swings through the same arc on the printing stroke of a type bar.

The augmented throw of the bellcrank is such that bellcrank abutment 130^a swings past the laterally shifted actuating lever abutment 136^a before the type bar completes its printing stroke. At the instant of type impact, as shown in Fig. 11, however, the ribbon vibrating train is arrested by stop lug 179 on the bellcrank striking the fixed stop formed by the under face of bracket 126. Since the vibrator or guide is positively connected with the bellcrank, overthrow of the

guide is prevented by this engagement of stops 179 and 126.

To render the guide inactive during making of stencils, lever 187 is shifted to its intermediate position and engaged in locking notch 184 as shown in Fig. 8 to slide lever 135 axially to its intermediate axially adjusted position, as shown in Fig. 7, wherein both pins are displaced from in front of 10 their actuating fingers on lever 135. On the printing strokes, of the type bars, with levers 135 adjusted as just described, all the ribbon actuating devices except bellcrank 124 and guide 113 move as before described, lever 15 135 swinging forward until the type bar completes its printing stroke. It will be observed from Figs. 7 and 12 that fingers 141 and 142 and walls 139 and 140 move forwardly at either side of the outer ends of the 20 pins 175 and 176, and that lever 135 is not moved far enough by the universal bar for wall 138 of said lever to engage and rock the pendent arm 130 of the bellcrank, so that the bellcrank and ribbon guide 113 remain in normal retracted position and the 25 actuated type strike the platen at the printing point over the upper edge of the ribbon.

What I claim is:

1. In a ribbon vibrating mechanism for 30 printing machines, the combination of a ribbon guide, and means for vibrating said guide to cause a ribbon to cover and uncover a printing point, said means comprising two members swinging in different directions about different parallel axes, one of said members being movable by the other to a position in which the guide is positioned to cover the printing point with a ribbon and each member has two opposed contacts with 35 the other member at two points at one side of its axis located different distances from its axis.

2. In a ribbon vibrator mechanism for 40 typewriting machines, the combination of an actuated lever and an actuating lever therefor having parallel pivotal axes, a ribbon guide positively connected with the actuated lever, and means for oscillating the actuating lever at the type strokes, one of said 45 levers having two oppositely facing portions, located different distances from its axis, first one and then both of which are engaged with the other lever, upon movement of the actuating lever in the direction transmitting 50 printing point covering movement to the actuated lever, for first moving the guide to covering position and then arresting movement of the guide to prevent overthrow of the guide.

3. In a ribbon vibrating mechanism for 55 typewriting machines, the combination of a ribbon guide, a guide vibrating lever positively connected with the guide, an actuating lever for said guide vibrating lever rockable about an axis parallel with the axis of

said guide vibrating lever and slidable longitudinally of its axis between two positions in which it is operative on said guide vibrating lever to impart thereto throws of different amplitude, means rigidly held to 60 said actuating lever engageable by the guide vibrating lever, only upon the guide reaching covering position and only when said actuating lever is axially adjusted to its position for imparting the shorter throw to the guide vibrating lever, for arresting movement of the 65 guide vibrating lever, and stationary means engageable by the guide vibrating lever only at the end of its longer throw to arrest movement thereof when the actuating lever is 70 axially adjusted to its position for imparting the long throw to the guide vibrating levers.

4. In a typewriting machine, the combination of a platen, key-operated types, a ribbon guide normally retracted from the printing point on the platen, a bellcrank having a forwardly extending arm directly and positively connected with the ribbon guide for 75 vibrating the guide up and down and a pendent arm provided with two transverse projections at opposite sides thereof different distances from the axis of the bellcrank, an upstanding actuating lever for the bellcrank rockable fore-and-aft and slidable transversely about an axis parallel with the axis of the bellcrank, a pair of transversely spaced tappets on said upstanding lever cooperative one at a time with different ones of said 80 projections on the pendent bellcrank arm, manually adjustable means for sliding said upstanding lever axially between two bellcrank actuating positions in each of which a different tappet is positioned in rear of its cooperative projection to set the lever for imparting covering throws of different amplitude to the guide, universal bar actuated 85 means for rocking said upstanding lever to move the guide upwardly to cover the printing point with a bichrome ribbon on the printing strokes of the types, an abutment on the upstanding lever located in the path of the forward movement of the pendent bellcrank arm only when the lever is positioned 90 for engagement of one of its tappets with that projection on the pendent bellcrank arm located farthest from the axis of the bellcrank, said abutment being nearer to the axis of the upstanding lever than to the axis of the bellcrank and engageable by the pendent arm of the bellcrank after a predetermined forward movement of said arm to positively arrest upward movement of the guide in position 95 for covering the printing point with the upper zone of a bichrome ribbon, and a fixed abutment engageable by the bellcrank, when the same is rocked a predetermined greater distance by the other tappet and pin, to positively arrest upward movement of the 100

guide in position for covering the printing point with the lower zone of the ribbon.

5. In a typewriting machine, the combination of a platen, key-operated types, a ribbon guide normally retracted from the printing point on the platen, a bellcrank having a forwardly extending arm directly and positively connected with the ribbon guide for vibrating the guide up and down and a pendent arm provided with two transverse projections at opposite sides thereof different distances from the axis of the bellcrank, an upstanding actuating lever for the bellcrank rockable fore-and-aft and slideable transversely about an axis parallel with the axis of the bellcrank, a pair of transversely spaced tappets on said upstanding lever cooperative one at a time with different ones of said projections on the pendent bellcrank arm, manually adjustable means for sliding said upstanding lever axially between two bellcrank actuating positions in each of which a different tappet is positioned in rear of its cooperative projection to set the lever for imparting covering throws of different amplitude to the guide, universal bar actuated means for rocking said upstanding lever to move the guide upwardly to cover the printing point with a bichrome ribbon on the printing strokes of the types, and two overthrow preventing abutments engageable by the bellcrank after different extents of throw thereof by the upstanding lever, one of said abutments being fixed relatively to the bellcrank and lever and engageable by the bellcrank only on the long throw thereof, and the other abutment being movable bodily transversely and fore-and-aft with the upstanding lever and in the path of and engageable by the bellcrank only on the short throw of the bellcrank.
6. In a typewriting machine, the combination of a platen, key-operated types, a reciprocating ribbon guide for a bichrome ribbon normally retracted downward to withdraw the ribbon from in front of the printing point on the platen, a bellcrank swinging about a transverse axis and having a forwardly extending arm directly and positively connected with the guide and a pendent arm, an upstanding actuating lever pivotally and slidably supported to swing fore-and-aft and slide transversely, a pair of tappets on said upstanding lever for transmitting forward movement to the pendent arm of the bellcrank at either of two points different distances from the bellcrank axis, manually adjustable means for sliding the upstanding lever transversely to either of three positions in two of which different ones of said tappets are cooperative with the pendent arm of the bellcrank and in the third of which neither of said tappets is positioned for transmitting movement to said bellcrank

arm, universal bar actuated means for rocking the upstanding lever forwardly on the printing strokes of the types in all transversely adjusted positions of the lever, an overthrow-preventing stop rigidly held to the upstanding lever forwardly into engagement with which the pendent arm of the bellcrank is adapted to be thrust by the short throw tappet upon the guide reaching its short throw covering position, said stop being withdrawn from the path of said bellcrank arm by transverse sliding adjustment of the upstanding lever to its position for rendering the long throw tappet effective on said bellcrank arm, and a fixed stop constantly in the path of the bellcrank against which the bellcrank is thrust by the long throw tappet upon the guide reaching its long throw covering position.

7. In a typewriting machine, the combination of a platen carriage, a platen on the carriage, a main frame, key-operated type bars on the main frame, case-shift means including a shift frame for the carriage movable up and down relatively to the main frame, a reciprocating guide for a bichrome ribbon normally retracted downward for withdrawing the ribbon from in front of the printing point, a bellcrank pivoted on the shift frame to swing about a transverse axis and having a forwardly extending arm directly and positively connected with the ribbon guide and a pendent arm, an upstanding lever pivotally and slidably supported on the shift frame to rock fore and aft and slide transversely, a pair of tappets on said upstanding lever for transmitting forward movements to the pendent bellcrank arm at either of two points different distances from the crank axis, a pair of stationary stops on the shift frame engageable by the bellcrank to determine its normal idle position and its maximum guide-lifting position respectively, a stop on the upstanding lever engageable by the bellcrank for determining the limit of the short throw guide-lifting movement of the bellcrank, manually operable means for sliding said upstanding lever transversely between two positions in which different ones of said tappets are effective on the pendent bellcrank arm, said stop on the upstanding lever being movable therewith into the path of the bellcrank when the lever is adjusted for rendering the short throw tappet effective and being movable out of the path of the bellcrank when the lever is adjusted to render the long throw tappet effective, and universal bar actuated means for rocking the upstanding lever forwardly uniformly in the different case positions of the shift frame on the printing strokes of the type bars.

8. In a typewriting machine, the combination of a platen carriage, a platen on the

- carriage, a main frame, key-operated type bars on the main frame, case-shift means including a shift frame for the carriage movable up and down relatively to the main frame, a reciprocatory guide for a bichrome ribbon normally retracted downward for withdrawing the ribbon from in front of the printing point, a bellcrank pivoted on the shift frame to swing about a transverse axis 5 and having a forwardly extending arm directly and positively connected with the ribbon guide and a pendent arm, an upstanding lever pivotally and slidably supported on the shift frame to rock fore-and-aft and slide transversely, a pair of tappets on said upstanding lever for transmitting forward movement to the pendent bellcrank arm at either of two points different distances from the bellcrank axis, a pair of stationary 10 stops on the shift frame engageable by the bellcrank to determine its normal idle position and its maximum guide-lifting position respectively, a stop on the upstanding lever engageable by the bellcrank for determining the limit of the short throw guide-lifting movement of the bellcrank, manually operable means for sliding said upstanding lever transversely between two positions in which different ones of said tappets are effective on the pendent bellcrank arm, said stop on the upstanding lever being movable therewith into the path of the bellcrank when the lever is adjusted for rendering the short throw tappet effective and being movable out 15 of the path of the bellcrank when the lever is adjusted to render the long throw tappet effective, a transversely extending lever mounted on the shift frame to swing about an up-and-down extending axis and having an arm engaged behind said upstanding lever in the different slidably adjusted positions thereof and an arm by which it is rocked, a fore-and-aft reciprocable actuator mounted 20 on the main frame having a slot perpendicular to the path of shift of the shift frame through which said last-mentioned arm of the transversely extending lever extends, and a type-bar-actuated universal bar mounted on the main frame connected with said actuator 25 to move the actuator rearwardly on the printing strokes of the type bars.
9. In a typewriting machine, the combination of a platen carriage, a platen on the carriage, a main frame, key-operated type bars on the main frame, case shift means including an up and down movable shift frame for the carriage, a reciprocatory guide for a bichrome ribbon normally retracted downward to withdraw the ribbon from in front 30 of the printing point, a bellcrank pivoted on the shift frame to swing about a transverse axis and having a forwardly extending arm directly and positively connected with the guide and a pendent arm, an upstanding 35 lever mounted on the shift frame to rock fore-and-aft and slide transversely, a bellcrank pivoted on the shift frame to swing about an up and down extending axis and having a fore-and-aft extending arm and a transversely extending arm, a transverse link 70 connecting said fore-and-aft extending arm of the last-mentioned bellcrank with said upstanding lever, a fore-and-aft extending link connected at its rear end with said transversely extending arm of the last-mentioned bellcrank, manually operable means on the main frame reciprocable fore-and-aft and connected with the forward end of said fore-and-aft extending link for adjusting the upstanding lever transversely, a pair of tappets 75 carried by said upstanding lever effective to transmit forward movement to the pendent arm of the guide actuating bellcrank in different slidably adjusted positions of the lever at two points different distances from the axis 80 of the bellcrank, a stop on the shift frame for limiting rearward movement of the pendent arm of the bellcrank, universal bar actuated tappet means for rocking said upstanding lever forward and adapted to arrest rearward movement thereof and cooperate with the pivotal mounting of the lever to guide said lever during sliding adjustments thereof for movement of said lever tappets into and out of operative relation with the pendent bell-crunk-arm, a spring connected with said upstanding lever to urge the same rearward, a stop on said upstanding lever located for engagement therebehind of the pendent bellcrank arm after a predetermined movement of the bellcrank by the short throw tappet on said lever and withdrawn from the path of said arm by a sliding adjustment of the lever rendering the long throw tappet effective, and cooperating stops on the 90 bellcrank and shift frame engageable only when the bellcrank is rocked by the long throw tappet.
10. In a ribbon vibrating mechanism, a ribbon guide, a bellcrank having a forwardly extending arm directly and positively connected with the guide and a pendent arm, an upstanding universal-bar-actuated lever having a forward thrust motion-transmitting connection, only, with said pendent bellcrank arm, and throw-limiting means carried by said upstanding lever forwardly against which said pendent bellcrank arm is adapted to be thrust by forward rocking of the upstanding lever through a predetermined arc. 100
11. In a typewriting machine, the combination of a main frame, a platen shift frame movable up and down, a tappet mounted on the shift frame to swing in a plane perpendicular to the path of case shifting movement of the shift frame, fore and aft reciprocable key-operated means on the main frame directly engaged with said tappet for swinging the same in all case positions of the shift frame, a ribbon guide, a bellcrank pivoted on a trans- 115

- verse axis on the shift frame and having a forwardly extending arm positively connected with the guide and a pendent arm, a lever on the shift frame rockable about an axis below the bellcrank axis and engaged by said tappet and having an upstanding arm adjacent the pendent arm of the bellcrank for pushing the pendent arm forwardly, and a stop on said upstanding arm normally spaced forwardly from the pendent arm and against which the pendent arm strikes at a different distance from its axis than the point of forward thrust thereagainst as the ribbon guide reaches printing point covering position.
12. In a typewriting machine, the combination of a main frame, a platen shift frame movable up and down, a tappet mounted on the shift frame to swing in a plane perpendicular to the path of case shifting movement of the shift frame, fore and aft reciprocable key-operated means on the main frame directly engaged with said tappet for swinging the same in all case positions of the shift frame, a ribbon guide, a bellcrank pivoted on a transverse axis on the shift frame and having a forwardly extending arm positively connected with the guide and a pendent arm, a lever on the shift frame rockable about an axis parallel with and below the bellcrank axis and engaged by said tappet and having an upstanding arm adjacent the pendent bellcrank arm for pushing the pendent arm forwardly, means for axially adjusting the lever to establish either of two forward pushing connections with the pendent arm, one of which connections is closer to the bellcrank axis than the other to increase the upward throw of the guide, a stop on said upstanding arm located in the path of forward movement of the pendent arm only when the lever is axially adjusted for the shorter throw of the guide and against which the pendent arm strikes at a different distance from its axis than the point of forward thrust thereagainst as the ribbon guide reaches lower printing point covering position; and a fixed stop on the shift frame always in the path of the bellcrank and engageable thereby only when the lever is adjusted for the longer throw of the guide.
13. In a typewriting machine, the combination of a main frame, a platen shift frame, a key-operated tappet on the shift frame, a ribbon guide, and a pair of directly coactive motion-transmitting levers pivoted on transverse axes on the shift frame and interposed between the tappet and guide, one of said levers being positively connected with the guide and the other being directly actuated by the tappet and having means for first exerting a guide lifting thrust on the guide connected lever and then opposing to such guide lifting thrust a counter thrust at a different distance from the axis of the guide connected lever to positively limit the extent of upward throw of the guide.
